BREECH MECHANISM FOR A RIFLE

Alonzo F. Gaidos, Redwood City, Calif.

Original application February 1, 1950, Serial No. 141,801.
Divided and this application December 8, 1952, Serial No. 324,856

2 Claims. (Cl. 89—187)

(Granted under Title 35, U. S. Code (1952), sec. 266)

The invention described herein may be manufactured and used by or for the Government for governmental purposes without the payment of any royalty thereon.

This invention relates to an improvement in a breech mechanism for a rifle and more particularly to the type of rifle as shown in my copending application, Serial No. 141,801, filed February 1, 1950, and now matured into U. S. Patent No. 2,688,203, of which this application is a division.

An object of this invention is the provision in a firearm of an improved breech lock adapted to unlock in direct response to the forward movement of a longitudinally reciprocable member.

It is a further object of this invention to provide improved means for actuating a breech lock of the type which is slidably disposed in the receiver at an acute angle to the vertical axis thereof.

Another object of this invention is to provide a direct manual means of unlocking the lock prior to hand-charging the firearm.

The specific nature of the invention as well as other objects and advantages thereof will clearly appear from a description of a preferred embodiment as shown in the accompanying drawings in which:

Fig. 1 is a fragmentary longitudinal cross-sectional right side view showing the breech lock in the locked position;

Fig. 2 is a fragmentary longitudinal cross-sectional right side view showing the lock in the unlocked position during manual operation of the actuator;

Fig. 3 is a cross-sectional view taken on lines 3—3 of Fig. 2;

Fig. 4 is a fragmentary perspective view of the actuator bar;

Fig. 5 is a cross-sectional view taken on lines 5—5 of Fig. 1;

Fig. 6 is a fragmentary perspective view of the rear end of the bolt; and

Fig. 7 is a perspective view of the firing pin retainer.

The particular embodiment of the invention chosen for the purpose of illustration, as shown in the drawings, comprises a receiver 12, a bolt assembly 13, a breech lock 14 and an actuating bar 15.

Receiver 12 is provided with a longitudinal bore 16 in the upper forward part thereof to receive bolt assembly 13. Receiver 12 has a downwardly depending rectangular portion 17 being provided with a vertical magazine opening 18 to receive a magazine 19. Portion 17 is also provided with an angular slot 20 to receive lock 14 which will be described later.

On the forward upper right side of receiver 12, angularly disposed above the axis, there is a longitudinal slot 30 provided to permit ejection of a fired round and for the accommodation of a bolt handle 31. On the rear surfaces of portion 17 of receiver 12 a transverse slot 37 is provided to receive a retainer 38 of a bolt return spring rod 39. A helical spring 41 surrounds bolt return spring rod 39 for a purpose to be later described.

2

Bolt assembly 13 comprises a bolt 21 cylindrical in contour having a firing pin tunnel 22 therein to receive a firing pin 23 of a conventional shape and such bolt is reciprocable in bore 16. A firing pin spring 24 surrounds pin 23 thereby biasing such pin rearwardly. Bolt 21 is provided on the rear end thereof with vertically positioned ways 25 to receive a firing pin retainer 26. Firing pin 23 has a reduced diametrical portion 27 on the rear end thereof which is slidably received in hole 28 of retainer 26. Bolt 21 is provided with a transverse slot 29 on the bottom near the rear end thereof to receive lock 14. Bolt 21 is provided with a longitudinally dove-tailed slot 32 on the forward right side angularly disposed above the horizontal axis thereof to receive bolt handle 31.

Retainer 26 is provided with a rectangular open slot 33 on the bottom end thereof to clear and permit a bolt return slide 34 to contact bolt 21. Bolt return slide 34 is provided with a depending body portion 35 having a longitudinal axial hole 36 therein. Bolt return slide 34 is slidably mounted on return spring rod 39 by means of hole 36. Bolt return slide 34 is biased forwardly by spring 41, thereby urging bolt 21 into the battery position.

Receiver 12 is provided with oppositely disposed longitudinal ways 40 on the left side thereof juxtaposed to slot 20 to slidably receive actuating bar 15 for reciprocating movement therein. Actuating bar 15 is provided with oppositely disposed ribs 44 that are receivable in ways 40 of receiver 12. Actuating bar 15 is provided with a lock actuating stud 43 protruding from the right side thereof. Lock 14 is provided with an angularly disposed slot 42 on the left side thereof arranged to slidably receive stud 43 of actuating bar 15. Oppositely disposed from stud 43, actuating bar 15 is provided with an arm 46 for manually operating lock 14 for a purpose to be described. An elongated slot 50 is provided on the left side of receiver 12 to permit movements of arm 46 therealong. Actuating bar 15 is spring-biased rearwardly by spring means (not shown) thereby camming the lock upwardly and locking the bolt in the battery position and such bar is actuated forwardly by gas pressure accumulating in an actuating cup (not shown) thereby camming the lock downwardly and unlocking the bolt from the battery position.

Operations

After the insertion of magazine 19, loaded with a double row of cartridges 47, into the magazine opening 18 of receiver 12 and secured therein by a magazine latch 48, lock 14 then is cammed downwardly out of slot 29 of bolt 21 by pressing forwardly on arm 46 with the thumb of the left hand, such arm being on the left side of the rifle. The bolt 13 is then retracted to the rear by handle 31 permitting the uppermost cartridge 47 in the magazine 19 to enter the chambering space between the bolt 13 and the end of a barrel 49 whereby on the return of the bolt to the battery position, the round is chambered in the barrel and the gun is charged for firing. After discharge of the cartridge 47 and when a conventional bullet has cleared the bore at the muzzle end (not shown) and while passing through the actuating cup (also not shown) the gases in escaping from such bore impinge upon the inner wall of such cup that is coupled with the actuating bar 15 which in turn moves such bar forwardly thereby camming the lock 14 downwardly.

It will therefore be apparent to one skilled in the art that application of the principle of the invention disclosed herein provides novel and improved firearm construction which is outstandingly characterized by a small number of parts with simplicity of configuration by such parts and also in cheapness of manufacture.

I claim:

1. In a recoil operated firearm having a fixed barrel

and a longitudinally reciprocal bolt, an angularly disposed bolt lock slidable into and out of vertical locking engagement with the underside of the bolt, said lock having a forwardly and upwardly inclined cam slot formed along one side thereof, a bolt lock actuator slidably mounted below the bolt for reciprocal movement parallel thereto, and a stud projecting transversely from the side of said actuator to engage in said slot in said bolt lock for camming said lock downwardly and rearwardly out of locking engagement with the bolt during forward movement of said actuator.

2. In a recoil operated firearm having a receiver, a barrel fixedly secured thereto, and a bolt slidably mounted in the receiver for longitudinal reciprocal movement to and from battery position, a slideable bolt lock angularly disposed in the receiver below the bolt, said lock having an upwardly projecting vertical locking portion movable into and out of locking engagement with the underside of the bolt, a bolt lock actuator slidably mounted below the bolt for reciprocal movement parallel thereto, said bolt lock having an upwardly and forwardly inclined cam slot formed along one side thereof, and a stud projecting transversely from the side of said actuator to engage in

5 said slot in said bolt lock for camming said lock downwardly and rearwardly out of locking engagement with the bolt during forward movement of said actuator whereby the angular disposition of said bolt lock relative to the vertical axis of the bolt permits said vertical locking portion to disengage from the underside of the bolt during the beginning of recoil travel and to reengage therewith during the conclusion of battery movement.
